Baldwin Wright

UNITED STATES PATENT OFFICE.

ALBERT PIHL, OF MURRAY, UTAH, ASSIGNOR TO GEORGE F. BORKMAN, OF SALT LAKE CITY, UTAH.

LOUD-SPEAKER SUPPORT.

Application filed April 7, 1924. Serial No. 704,798.

To all whom it may concern:

Be it known that I, ALBERT PIHL, a citizen of the United States, and resident of Murray, in the county of Salt Lake and

5 State of Utah, have invented certain new and useful Improvements in Loud-Speaker Supports, of which the following is a specification.

An object of the invention is to provide a 10 support for a loud speaker which will be simple in construction and pleasing in appearance, as well as lasting and durable.

Another object is to provide such a support that will support a receiver and the 15 loud speaker in proper relation to each other so that they can be connected to any suitable receiving set.

Another object is to provide a support which will protect the receiver against dust 20 and dirt and damage during use.

Other objects will be apparent from the following detailed description and appended claims.

In the drawings:

25 Figure 1 is an elevation of the support or case for the speaker and receiver with the parts in operative relation.

Figure 2 is a vertical section through the support, showing the receiver in position.

30 The support comprises a base 1 of any desired form or contour which may be made of various materials. It will preferably be circular in form and large enough to be stable when in use. The top 2 will be some-

35 what smaller and of similar outline, and preferably made of some moulded insulating material. The top and bottom are spaced apart by a glass cylinder 3 which fits within a shoulder 4 on the base and a 40 similar shoulder 5 on the top. A plurality of screw bolts 6 pass through the base and are threaded into the top to hold the parts clamped together.

The top is provided with a central cylindrical hole which may be threaded at its 45 lower end. A receiver A which in itself forms no part of the present invention and may be of varied type, is provided with an attaching member 8 in the form of a disc 50 fastened to the receiver by screws 9 and hav-

ing a projecting tubular portion or nipple 10 overlying the diaphragm of the receiver, the outer portion of which portion 10 is threaded to screw into the opening 7. The receiver is provided with the usual binding 55 posts 11 to which are attached the terminals of the cord 12 which passes through an opening 13 in the bottom of the base and through another opening 14 in the side flange of the base. This flange may of course be made 60 with openwork, or in other form which would avoid the necessity of the opening 14.

The cord 12 may be connected to any desired form of receiving set B or to any desired receiver of wireless or wire signals. 65 The loud speaker 15 has its lower end formed to fit in the upper portion of the opening 7 as indicated in Figure 1.

The invention provides a simple form of support for the loud speaker and receiver, 70 and the latter is protected from dust, dirt, or accidental injury during handling. The parts can be disassembled when desired by merely removing the screw bolts 6, and another receiver substituted therefor or cords 75 of different length attached thereto. The whole may be made in various designs and is easily moved from one place to another.

Obviously various details can be modified and changed without in any manner departing from the spirit of the invention, and the invention is therefore to be regarded as limited only by the scope of the appended claims.

I claim as my invention:

1. A loud speaker unit comprising in combination a supporting casing including a top having an opening, a loud speaker supported on said top and having its inlet end in communication with said opening, a receiver disposed within the casing, and means for supporting said receiver from said top including a plate attached to said receiver, and a nipple fixed to the plate and extending into the opening of the top, said nipple having a threaded connection with the wall of said opening.

2. A support comprising a base member, top member, and intermediate cylindrical glass member together with means for secur-

ing said members together, in combination with a receiver, a plate attached thereto and provided with a central nipple, and means for securing said nipple to the top member.

3. A support comprising a base member, a top member having an opening therethrough, an intermediate casing member and

means for securing said parts together, in combination with a receiver, a plate attached thereto and having a projecting portion threaded into the opening in the top member. 10

In testimony whereof, I have hereunto subscribed my name.

ALBERT PIHL.
